UNITED STATES PATENT OFFICE

CLARENCE DILLON AND DILLARD DAUGHETEE, OF RICHLAND CENTER, WISCONSIN

VIOLIN BOW

Application filed September 21, 1929. Serial No. 394,200.

This invention relates to musical instruments, and has more particular reference to a violin bow.

The primary object of this invention is to provide an improved means for securing the ends of the hair strings of a violin bow to the frog and enlarged end of the bow staff, whereby the horse hair strings of the bow may be readily removed or replaced without any possibility of damage being inflicted upon the bow.

A still further object of the invention is to provide means for securing the ends of the horse hair strings of the bow to the frog and staff end, whereby the removal or replacement of bow strings may be accomplished within the period of but relatively short time and a cheaper and less inexpensive manner than in the former methods as have been heretofore in vogue.

A still further and very important object of the invention is to provide a pair of especially designed clips adapted for receiving the knotted ends of the bow strings one clip of the pair being adapted for engagement with the conventional frog of a violin bow, and the other clip adapted to engage with the enlarged lateral end of the bow staff.

Another important object of the invention is to provide a device of the character above mentioned which is comparatively simple in construction, strong, thoroughly reliable, practical and efficient in use and operation, and otherwise well adapted for the purpose intended.

Other objects and advantages of the invention will become apparent during a study of the following description, taken in connection with the accompanying drawings, 40 wherein:

Figure 1 is a side elevational view of a violin bow constructed in accordance with the present invention and showing the manner of applying my invention thereto.

Figure 2 is a longitudinal sectional view taken through the frog and clip applied thereto.

Figure 3 is a similar view taken through the enlarged lateral end of the bow and the clip applied thereto.

Figure 4 is a perspective view of the shoe or clip adapted to be engaged with the frog of the violin bow.

Figure 5 is a similar view of a slipper member adapted to be engaged with the enlarged lateral end of the bow staff.

With reference more in detail to the drawings, it will be seen that we have illustrated a conventional violin bow comprising the usual staff 5 which staff 5 terminates at one end in a relatively large lateral end portion 6. At its opposite end slidably mounted on the staff 5 is a conventional frog 7, while the reference character 8 designates the adjusting knob for actuating the frog 7.

As comprehended by the present invention, the enlarged lateral end 6 of the bow staff is provided with a socket 9 formed therein and extending inwardly from the lower end of said portion 6. A slipper member designated generally by the reference character 10 comprises a base 11 and a toe member 12, which toe member 12 is adapted, being in the nature of a socket, to receive the laterally extending toe portion 13 of the staff end 6, so that the base 11 of the slipper member extends along the entire bottom face of said end 6 as clearly shown to advantage in Figure 3. On opposite longitudinal edges thereof the base member 11 is provided with upstanding spring like fingers or retaining flanges 14-14 adapted to frictionally engage the end 6 on opposite sides of said end for retaining the slipper member 10 thereon.

Further, the base 11 is provided rearwardly of the toe 12 with a hole or aperture 15 adapted to register with the socket 9. At the end remote from the toe 12 the slipper 10 is provided with a sleeve 16, the material forming the base 11 at said end being provided with relatively long extensions on opposite sides thereof, which extensions are bent downwardly as at 17 and then inwardly in parallelism to the base as at 18 the end portions 18 having their adjacent edges disposed in abutting relation and thus forming with the base 11 the said sleeve 16.

The horse hairs forming the bow strings 19 have their ends suitably knotted as at 20 and 21, respectively. One end of the bow

strings 19, which for convenience is designated as at 21, is adapted to pass through the aperture 15 in the base of the slipper member 10 for reception into the socket 9, it being understood that the knot 21 is of sufficient diameter as to prevent the pulling of the bow strings through the aperture 15 when the knotted end 21 is retained in the socket. The horse hairs of the bow strings 19 are then passed through the sleeve 16, and at the other end the bow string is passed through a similarly formed sleeve 22 formed on the forward end of the base member 23 of a frog engaging shoe member designated generally by the reference character 24.

The frog engaging member or shoe 24 is provided on its base portion 23 in close proximity to the sleeve 22 with an aperture 25 to which the other end of the bow strings 19 is passed so that when knotted as at 20 this said end of the bow strings cannot be pulled through the aperture or opening 25. Secured to the base member 23 of the shoe 24 adjacent the opening 25 is a semi-circular band 26 formed of metal or any other suitable material which is adapted to be disposed about the toe portion 7' of the frog 7. The base 23 extends along the bottom of the frog 7 for the full length of the frog, and at its rear end said base 23 merges into a relatively wide heel 27 forming a seat for the reception of the rear lower end or corner of the frog 7. In forming the heel of the shoe 24 the base is enlarged at its rear end and the enlarged end 27 of the base 23 has a flange 28 extending transversely of the base and along opposite sides thereof at the extreme end of said base for engaging with the rear end and opposite sides of the frog 7.

In actual practice, the ends of the bow strings 19 are passed through the openings 15 and 25 respectively, of the slipper member 10 and shoe member 24, which ends are then knotted as at 20 and 21. The slipper member is then disposed upon the lateral end portion 6 of the staff 5 in the manner before explained. The knot 8 is then rotated so as to move the frog 7 longitudinally of the staff 5 inwardly toward the end 6 and the shoe member 24 is then applied to the frog 7 in the following manner; the band 26 is first slipped over co-extension 27', after which the base member 23 of the shoe is pressed upwardly against the bottom face of the frog 7 so that the lower left hand corner of the frog 7 is received in the heel of the shoe, whereby the flange 28 engages the frog 7 to bear against one vertical end edge of the frog and against the opposite side faces of the frog as suggested in Figures 1 and 2. The knob 8 may then be rotated in the opposite direction for moving the frog 7 rearwardly of and away from the staff end 6 thus drawing taut the horse hairs of the bow strings 19.

The mechanism connecting the operating knob to the frog 7 is conventional, forming no part of this invention and, therefore, it is deemed that a detailed showing of such is unnecessary and would be superfluous.

It is believed that from the foregoing description taken in connection with the accompanying drawings, a clear understanding of the construction, operation and utility of an invention of this nature will be had. A more detailed description thereof is, therefore, deemed unnecessary.

Even though we have herein shown and described the preferred embodiment of our invention, it is to be understood that the same is susceptible to certain changes falling within the scope of the spirit of the invention as herein described, it being further understood that we do not wish to limit ourselves other as would be required in view of the state of the prior art and the scope of the appended claims.

Having thus described our invention, what we wish to claim as new is:—

1. In combination, a violin bow, a shoe member embodying a base adapted to extend along the bottom edge of the frog of the bow, said base terminating at one end into a heel portion adapted for the reception of the rear end of said frog, and means at the other end of the base for securing the latter in the toe portion of the frog, said base at said last mentioned end having an aperture formed therein adapted to receive the knotted ends of a bow string, and a sleeve carried by said base and said last mentioned end, and through which the end portions of the bow strings is adapted to extend, and a slipper member having a toe portion adapted to receive the toe of the enlarged end of the violin bow, said slipper member further embodying a base having an aperture formed therein adapted to receive one knotted end of the bow string.

2. In combination with a violin bow, wherein the same comprises a staff, terminating at one end in a laterally extending enlarged end portion merging into a toe, and a frog slidably mounted on said staff, a pair of bow string retaining clips, one clip of said pair adapted to engage said frog, said one clip embodying a base having an aperture formed therein and a sleeve disposed on the base adjacent said aperture, and the string of said bow adapted to be passed through said sleeve and said aperture, said string at said end being knotted, and the other of said clips comprising an apertured base portion, said last mentioned clip being adapted to be secured to the lateral end of said staff with the aperture in registry with a socket formed in said staff end, the base portion of said last mentioned clip being provided with a sleeve formed thereon in close proximity to the aperture whereby the other end portion of the bow strings may be passed therethrough

and through said aperture for reception into the socket in said staff end.

3. In combination, means for securing the ends of a bow string to the frog and lateral end of the bow staff, said means comprising a pair of clips, one clip of said pair adapted to be secured to the frog of the bow, and comprising a heel portion adapted to receive the rear end of said frog, said one clip having an apertured base portion for the reception of a knotted end of the bow string, and the other clip comprising a toe portion adapted to receive the toe of the lateral end of said bow staff, said last mentioned clip being also provided with an apertured base portion for the reception of the knotted end of the bow string prior to its reception into a socket provided therefor in said staff end, and the base portions of each of the said clips being provided on opposite sides thereof with retaining flanges for engagement with the adjacent sides of the frog and staff end respectively.

4. In combination with a violin bow, a shoe member, and a slipper member, said shoe member being adapted for engagement with the frog of the violin bow, said shoe member being formed at one end with a heel portion adapted to receive one end of the frog and at its opposite end having a retaining band mounted thereon for engagement with the toe of the frog, said shoe at the last referred to end having an aperture formed therein for the reception of one end of the violin bow string, and said slipper member being formed at one end with a toe portion adapted to receive the laterally extending toe portion of the enlarged end of the violin bow staff, and an apertured base portion adapted to receive the opposite end of the violin bow string, and retaining clips extending upwardly on opposite sides of the base portion of said slipper member for frictional engagement with the adjacent side of said staff end.

5. In a device for detachably securing one end of a bow string to a violin bow, a clip member including an apertured base for receiving in the aperture thereof, a knotted end portion of the bow string, a sleeve formed on one end portion of said apertured base for guiding said knotted end portion of said bow string, and means integral with the base, for engagement with a suitable part of the violin bow for retaining said clip in engagement with said suitable part of the violin bow.

6. A clip for detachably securing one end of a bow string to a suitable part of a violin bow comprising a base portion apertured adjacent one end for receiving in the aperture the knotted end portion of a bow string, said base at the opposite end thereof having means for engagement with a suitable part of the violin bow for retaining said clip

against longitudinal movement relative to the violin bow in one direction, additional means carried by said clip and integral with said base for engaging said parts of the violin bow for retaining said clip in engagement with said part of the violin bow, and said base having a transversely extending loop member integral therewith, and extending from one face of the base of the clip in proximity to the aperture in the base, said loop portion adapted to receive therethrough a portion of the bow string at the knotted end of the bow string.

In testimony whereof we affix our signatures.

CLARENCE DILLON.
DILLARD DAUGHETEE.
